(57) **CLAIM**

The ornamental design for a rear fender, as shown and described.

DESCRIPTION

FIG. 1 is a front right perspective view of a rear fender according to the present invention.

FIG. 2 is a rear left perspective view of the rear fender of FIG. 1.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is another front view of the rear fender shown in FIGS. 1-8, but mounted on a vehicle and with the rest of the vehicle shown in broken lines to show environmental aspects thereof. More particularly, in FIG. 9, the claimed design is the image of the front fender that is surrounded by broken lines. The broken lines form no part of the claimed design, but are instead included to show environmental aspects thereof.

The inventors contemplate a mirror image of a fender on the opposite side of vehicle.
